GAMEBOARD

Silas C. Vines, 927 S. Windsor, Stockton 5, Calif., and
Murrel O. Short, 3911 Gross Road, Santa Cruz, Calif.

Filed May 29, 1963, Ser. No. 75,123

Term of patent 3½ years

(Cl. D34—5)

FIG. 1

FIG. 2

FIGURE 1 is a top plan view of a gameboard showing our new design; and

FIGURE 2 is a side elevational view thereof.

We claim:

The ornamental design for a gameboard, substantially as shown.
